SPRING ASSEMBLY

Frank S. Price, Holland, Mich., assignor to
Charles Karr Company, a corporation of Michigan

Application April 22, 1938, Serial No. 203,499

2 Claims. (Cl. 5—260)

The invention relates to spring assemblies for mattresses or cushions, and its objects are to strengthen and generally improve the side margins of the assembly.

5 The invention consists mainly in forming the ends of the transverse rows of spirals of twin springs of special construction, and in various novel details of construction, as hereinafter pointed out and as illustrated in the accompanying drawings, in which

Fig. 1 is a detail plan view of the improved mattress;

Fig. 2 is a detail section on the line 2—2 of Fig. 1;

15 Fig. 3 is a detail edge view of the spring assembly;

Fig. 4 is a perspective of a pair of marginal springs in substantially the relative positions they occupy when assembled; and

20 Fig. 5 is a detail elevation of the end of a transverse row of spirals of slightly different form than as shown in Fig. 3.

As shown in Fig. 1, the spring assembly comprises a series of transverse rows, as 10, 11 and 25 12, of spirals, as 13, the number and length of the rows varying with the surface area of the assembly. The adjacent rows are, as usual, tied together by helicals 14, within the turns of which the end turns of the spirals are engaged; a 30 similar helical 15 forming the binder of each end of the assembly. The ends of the several rows are, however, formed of two spirals, as 16, 17, of correspondingly less major diameter than the inner spirals.

35 The end turns, as 18, 20, of each of these end spirals enter and interlock with the adjacent helical, in one instance having an offset, as 19, inclosing a turn of the helical, and in the other, as 19a, entering the helical laterally, extending 40 along its bore toward its end and emerging between adjacent turns, being then offset outwardly a short distance, as shown at 21, and extended to, interlocking with and terminating in the companion helical of the row, as shown at

45 22. The portion to which the numeral 21 is applied in Fig. 4 is straight, and, with corresponding elements of the several rows of the spirals, constitutes the side binder of one face of the assembly. The companion end spiral is similarly 50 formed and engaged, and, being inverted relatively to its mate, forms a section of the side binder of the opposite face of the assembly.

The twin springs may be interlinked. Preferably the interlinking is limited to their end turns, as shown in Figs. 1 and 3, the intermediate turns being of slightly reduced diameter to avoid interference. By this arrangement all danger of clicking under compression is eliminated, the engagement of the end turns of the

spirals with the helicals preventing their relative approach.

By the use at each face of the assembly of an end extension of one of the twin spirals for connecting the adjacent cross helicals, undesirable 5 flexibility of the edge binder is avoided. Greater stiffness at the margin of the assembly than elsewhere is desirable, whether the use is as a seat or for reclining. As the stiffness of a spiral is increased by reducing the diameter of its coil, 10 either throughout the length of the spring or by giving it the hour glass shape, the employment of a smaller gauge wire for the twin spirals than for those within the border of the assembly may be resorted to for avoiding the necessity 15 for increasing the diameter of the transverse helicals beyond the size required for accommodating the two strands of inner adjacent spirals of contiguous rows. As three strands of a wire of given size require the use of a helical of but .075 20 times greater diameter than is required for enclosing two strands of the same gauge, the present invention calls for the use of wire for the twin spirals of but one gauge less than is used in the inner spirals, in order that clicking with- 25 in the helicals may be avoided.

I claim as my invention:

1. A wire mattress formed of spirals arranged in transverse rows, such rows being bounded and connected by helicals engaging the end turns of 30 contiguous spirals, an end of each row comprising a pair of spirals of reduced diameter, the end turns of each entering and interlocking with an adjacent helical, one of such ends being prolonged and forming a terminal extending across 35 the end of the row and entering and interlocking with the companion helical of such row, the two end spirals being relatively inverted, whereby their cross extending terminals form sections of the side binders in the planes of the two faces of 40 the assembly.

2. A wire mattress formed of spirals arranged in transverse rows, such rows being bounded and connected by helicals engaging the end turns of 45 contiguous spirals, an end of each row comprising a pair of spirals of reduced diameter, the end turns of each entering and interlocking with the adjacent helical, one of such ends being prolonged and forming a terminal extending across 50 the end of the row and entering and interlocking with the companion helical of such row, the two end spirals being relatively inverted, whereby their cross extending terminals form sections of the side binders in the planes of the two faces 55 of the assembly, the end turns of the pairs of smaller spirals being interlinked and of greater diameter than the intermediate turns.
